CLAIM

The ornamental design for a container, as shown and described.

DESCRIPTION

FIG. 1 is a front top perspective view of container, showing all 6 panels in an assembled configuration;

FIG. 2 is a top perspective view of one panel, showing it separately from the other panels for ease of illustration;

FIG. 3 is an exploded view of the container, showing 5 panels for ease of illustration;

FIG. 4 is a perspective view of the container, showing one panel separated from the other panels;

FIG. 5 is a front elevational view of the container;

FIG. 6 is another front top perspective view of the container, showing all 6 panels in an assembled configuration;

FIG. 7 is a front elevational view of one panel, showing it separately from the other panels for ease of illustration;

FIG. 8 is a top plan view of one panel, showing it separately from the other panels for ease of illustration; and,

FIG. 9 is a bottom plan view of one panel, showing it separately from the other panels for ease of illustration.
